UNITED STATES PATENT OFFICE.

LOUIS CASTELLI, OF NORTH BERGEN, NEW JERSEY.

WINDOW OR WINDOW-SCREEN STOP.

Application filed June 9, 1923. Serial No. 644,504.

To all whom it may concern:

Be it known that I, LOUIS CASTELLI, a citizen of the United States, and a resident of North Bergen, in the county of Hudson and State of New Jersey, have invented a new and Improved Window or Window-Screen Stop, of which the following is a full, clear, and exact description.

The present invention has relation to a stop which is adapted to be carried by a vertically sliding closure for the purpose of holding and retaining the same in various vertically adjusted positions against casual displacement and has particular reference to a device of this character which is designed for use in connection with windows or window screens.

The outstanding object of the present invention resides in the provision of an extremely simple and inexpensive device which when applied to a vertically sliding closure such as a screen or window sash, functions to normally engage with the frame or guide within which the same is mounted to normally hold the same in position when raised, and which is capable of manipulation to effect its release when it is desired to lower said closure.

More specifically the invention contemplates a window or window screen stop which includes an attaching member and a pivoted locking element, the free end of which is normally forced into engagement with the frame in which the screen or window is mounted by a spring or other suitable element which engages therewith.

As a still further object the invention resides in the provision of a device of the character set forth which is readily applicable to a screen, window sash or other vertically slidable closure, and which is thoroughly reliable and highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a front view of the device.

Fig. 2 is a side view of the pivoted element.

Fig. 3 is a side view of the device.

Fig. 4 is a diagrammatic front view of the same in applied position.

Referring to the drawings by characters of reference the device includes an attaching member which consists of a strip 10 of sheet metal or any other suitable material, the upper end of which is provided with a forwardly bent flange 11 and a downwardly bent apron 12 which is arranged in spaced parallel relation to a portion of the body. A lever 13 having a transverse central aperture 14 is arranged between the apron and the body and is pivotally associated therewith by means of a transverse pivot pin 15 which extends through the aperture 14 and aligned apertures 16 and 17 in the apron and body. At one of the free ends the lever 13 is provided with an enlarged head 18 and at its opposite free end with an angularly disposed manipulating handle 19. A leaf spring 20 is attached to the under side of the flange as at 21 and its free end engages with the upper side of the lever between its pivotal point 15 and the manipulating handle 19 whereby the end having the enlarged head 18 is normally swung in an upward direction. The body portion of the attaching member 10 is provided with a forwardly projecting stop pin 22 with which the under side of the lever between its pivotal point 15 and the manipulating handle 19 is adapted to coact as a stop for limiting the upward swinging movement of the head 18.

In use and operation of the device the body portion of the attaching member 10 is secured in flat contact to the side rail of a window sash or screen A, as illustrated in Fig. 4, with the apron disposed at the upper end and with the headed end 18 of the lever spaced from the side edge of said side rail so that the maximum space between the inner edge B of the window frame C is slightly less than the distance between the pivotal point of the lever and the outer end of the head 18. It thus follows that when the screen or window sash A is raised, the spring 20 functions to swing the headed end 18 of the lever upwardly, thereby forcing the same into engagement with the inner edge B of the window frame C. Due to the fact that the length between the outer end of the head and the pivotal point of the lever is greater

than the maximum distance between the inner edge B and the pivotal point, it is obvious that a jamming action is set up which serves to support and retain the screen or sash in its raised position. When it is desired to lower the ash or screen A, the manipulating handle 19 is grasped and the lever is swung on its pivot to lower the headed end 18.

10 I claim:

1. As a new article of manufacture, a device for retaining vertically sliding closures in various vertically adjusted positions against gravitational downward movement under their own weight, comprising a lever pivoted to the closure and having a head at one end and a manipulating handle at its opposite end, means engageable with the headed end of the lever for normally swinging said end down and the headed end up for engagement with the frame of the closure, and means for limiting the upward swinging movement of the headed end, as and for the purpose specified.

2. As a new article of manufacture, a device for retaining vertically sliding closures in various vertically adjusted positions against gravitational downward movement under their own weight, comprising an attaching member secured to said closure, a lever pivoted to said member and having a head at one end and a manipulating handle at its opposite end, means on the attaching member engageable with the headed end for normally swinging the said end down and the headed end up for engaging the

frame of the closure to set up a jamming action, and means for limiting the upward swinging movement of the headed end, as and for the purpose specified.

3. The combination with a vertically slideable closure and the frame in which the same is mounted, of a device for retaining the same in vertically adjusted positions against gravitational downward movement under their own weight, comprising a base member secured to said closure, a lever pivoted to said base member having an outer headed end in which the distance between said headed end and the pivotal point is greater than the maximum distance between the inner side frame and said pivotal point, means for normally swinging the lever in a direction to engage the headed end with the inner side of the frame to set up a jamming action for retaining the closure against downward movement, said lever having its opposite inner end provided with a manipulating handle for releasing the same to permit of the lowering of the closure, and a stop element on said base member engageable with the lever for limiting the upward swinging movement of the headed end thereof.

In testimony whereof, I have signed my name to this specification, this 23rd day of May, 1923.

LOUIS CASTELLI.
